CLAIM

The ornamental design for a molded surface of a concrete
block, as shown and described.

DESCRIPTION

FIG. 1 is a perspective view of a molded surface of a
concrete block, according to our design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawing views are included for the
purpose of illustrating portions of the molded surface of a
concrete block that form no part of the claimed design.
